UNITED STATES PATENT OFFICE.

WALTER G. LYNCH, OF ROANOKE RAPIDS, NORTH CAROLINA.

CIRCUIT-CLOSER.

1,193,705.

Specification of Letters Patent.

Patented Aug. 8, 1916.

Application filed March 10, 1915. Serial No. 13,511.

To all whom it may concern:

Be it known that I, WALTER G. LYNCH, a citizen of the United States, residing at Roanoke Rapids, in the county of Halifax and State of North Carolina, have invented certain new and useful Improvements in Circuit-Closers, of which the following is a specification, reference being had to the accompanying drawings.

- 10 My invention relates to certain improvements in circuit closers, and it is an object of the invention to provide a novel and improved device of this general character comprising a movable contact mounted for rocking movement and coacting with continuous parallel spaced conductors and wherein said movable contact is normally maintained in an inoperative adjustment through the medium of a fusible member.
- 15 The invention consists in the details of construction and in the combination and arrangement of the several parts of my improved circuit closer whereby certain important advantages are attained and the device is rendered simpler, less expensive and otherwise more convenient and advantageous for use, all as will be hereinafter more fully set forth.
- 20 The novel features of the invention will hereinafter be definitely claimed.
- 25

In order that my invention may be the better understood, I will now proceed to describe the same with reference to the accompanying drawings, wherein—

- 30 Figure 1 is a view partly in longitudinal section and partly in elevation illustrating a circuit closer constructed in accordance with an embodiment of my invention; and Fig. 2 is an elevational view with a portion of the casing broken away, illustrating certain details of construction of my improved circuit closer as herein embodied.

35 As disclosed in the accompanying drawings, my improved circuit closer consists of a block 23 which is formed of insulating material, a base plate or casing 24 which incases the block and a gravity contact carrying arm 25. The block 23 is provided with two longitudinal bores or channels which are parallel to each other and are adapted to receive the two wires 26 and 27. These wires 26 and 27 exterior of the block 23 are ar-

ranged in an insulating jacket 28'. In the block 23 is formed a recess 28, which is relatively deep and is considerably wider than the space between the wires 26 and 27. The arm 25 is pivoted on a pin 29, to a lug or ear 30 located above the recess 28, when the block is secured to the wall. The lower free end of the arm 25 is provided with a wedge-shape contact or bridge piece 31 on that face which is adjacent the block 23. The other face of the arm carries a weight 32 which is heavy enough to cause the member 31 to force its way in between the wires 26 and 27 when the cord 33 which normally holds the arm in open circuit position, as in Fig. 1, is severed by burning.

The casing 24 is secured by screws or other suitable fastening means to the wall, so as to hold the block in position thereagainst. It will be seen that when the contact or bridge piece 31 enters the recess 28 and wedges itself between the wires 26 and 27, these members will be electrically connected.

In reduction to practice, it has been found that the form of this invention illustrated in the drawings, and referred to in the above description as the preferred embodiment, is the most efficient and practical; yet realizing that the conditions concurrent with the adoption of this device will necessarily vary, it is desirable to emphasize the fact that various minor changes in details of construction, proportion and arrangement of parts may be resorted to, when required, without sacrificing any of the advantages of this invention, as defined by the appended claim.

What is claimed is:—

90
A circuit closer including a wall block of insulating material provided with a recess opening through its outer face, continuous parallel spaced conductors passing through the block and intersecting the recess, those portions of the conductor contained within the recess being spaced from the side and bottom walls thereof, a pivoted arm mounted upon the block, the pivot point of said arm being above the recess, a wedge-shaped contact member carried by the free end of the arm, a weight member mounted upon the arm at the free end thereof, and a fusible member coacting with the arm for normally

holding the same in open circuit position, wherein the contact member is withdrawn from the recess, said arm being adapted to fall by gravity when released, whereby the
5 wedge-shaped contact member is wedged between those portions of the conductors intersecting the recess.

In testimony whereof I hereunto affix my signature in the presence of two witnesses.

WALTER G. LYNCH.

Witnesses:

R. L. TOWE,
Mrs. HULDAH E. LYNCH.
